(57) **CLAIM**

The ornamental design for an emergency lighting unit, as shown and described.

DESCRIPTION

FIG. 1 is a front perspective view of an emergency lighting unit of the present invention.

FIG. 2 is a front view of the emergency lighting unit of the present invention.

FIG. 3 is a top plan view of the emergency lighting unit of the present invention.

FIG. 4 is a back plan view of the emergency lighting unit of the present invention.

FIG. 5 is a bottom plan view of the emergency lighting unit of the present invention.

FIG. 6 is a right side plan view of the emergency lighting unit of the present invention; and,

FIG. 7 is a left side plan view of the emergency lighting unit of the present invention.

The broken lines shown on the drawings form no part of the claimed design.
